DESIGN FOR A BLOUSE

Benjamin Shander, Philadelphia, Pa.

Application November 30, 1939, Serial No. 88,570

Term of patent 3½ years

To all whom it may concern:

Be it known that I, Benjamin Shander, a citizen of the United States, residing in the city of Philadelphia, in the county of Philadelphia, and State of Pennsylvania, have invented a new, original, and ornamental Design for a Blouse, of which the following is a specification, reference being had to the accompanying drawing, forming part thereof.

Fig. 1 is a front view of a blouse showing my design, and

Fig. 2 is the rear view thereof.

The characteristic feature of my design resides in the combination, on the specific drop yoke blouse disclosed, of the specific front button panel which is stitched in the manner and arrangement shown, in association with the matching stitch trim on the pocket member, as shown.

I claim:

The ornamental design for a blouse, substantially as shown and described.

BENJAMIN SHANDER.
